UNITED STATES PATENT OFFICE.

JACOB J. ENGBRECHT, OF ROTHIEMAY, MONTANA.

SHINGLING-GAGE.

1,172,775.

Specification of Letters Patent. Patented Feb. 22, 1916.

Application filed April 5, 1915. Serial No. 19,296.

To all whom it may concern:

Be it known that I, JACOB J. ENGBRECHT, a citizen of the United States, residing at Rothiemay, in the county of Musselshell, 5 State of Montana, have invented certain new and useful Improvements in Shingling-Gages; and I do hereby declare the following to be a full, clear, and exact description of the invention, such as will enable others 10 skilled in the art to which it appertains to make and use the same.

This invention relates to shingling gages and more particularly to a gage whereby subsequent rows of shingles may be conveniently laid in alinement with a uniform 15 width thereof exposed to the weather.

An object of the invention resides in the provision of a shingling gage in which the attaching members thereof may be readily 20 released from or engaged with a roof to properly position the gage relatively to the latter, such engagement or disengagement of the members being simultaneously effected upon manipulation of the straight 25 edge portion of the gage from any point throughout its length at which the operator may be stationed.

With the above and other objects of similar nature in view, the invention consists in 30 the construction, combination and arrangement of parts, set forth in and falling within the scope of the appended claim.

In the drawing:—Figure 1 is a side view of the gage in position for use. Fig. 2 is a 35 top plan view thereof. Fig. 3 is a sectional view taken on the line 3—3 of Fig. 2, and Fig. 4 is a perspective view of one of the attaching members of the gage.

Referring now more particularly to the 40 drawing, the gage comprises essentially, a straight-edge A, and spaced attaching members B arranged adjacent the ends of said straight-edge.

In detail the attaching members B each 45 comprises a support 10, including a base plate 11, and upwardly extending spaced ears 12 rising from opposite side edges of said base plate. Secured as at 13 to the rear portion of the base plate is one end of a leaf 50 spring 14, the same being bowed upwardly and forwardly from its point of connection and having its free end extended between and beyond the ears 12, there being provided at the extremity of said free end portion of 55 the spring depending spurs 15 which are adapted to engage and penetrate the upper

face of a shingle whereby to secure said member relatively thereto.

Connecting the upper ends of the ears 12 is a transverse pin 16 and pivotally engaged 60 on said pin is a rule arm 17, said arm having spaced openings therein through which are inserted screws 18 or other suitable attaching means whereby the straight edge A is rigidly supported therefrom. Delineated 65 upon the upper face of the arm 17 are suitable graduations 19 by which the straight-edge may be properly positioned with relation to the arm to effect the desired lap of each subsequent row of shingles. 70

Likewise mounted upon the pin 16 and between the ears 12, is a lever 20 provided with a cam face 21 adapted to engage and depress the free end of the spring 14 and thus securely hold the spurs 15 in gripping 75 relation with the adjacent shingle. The lever 20 when in operative position is disposed with its extremity engaging the upper face of the arm 17, and to secure same in such position there is employed a locking ring 22, 80 said ring having its ends slidably engaging in slots 23 arranged longitudinally of the arm and being thus readily manipulated to secure or release said lever.

To place the gage in position for use, the 85 forward base portion 10 of each of the attaching members is inserted between two lapped shingles C in adjacent rows with the front edges of the ears 12 engaging the lower end of the top shingle, the straight 90 edge A being in this manner disposed upon the "butts" of the upper row of shingles and parallel with the transverse edges thereof. The levers 20 are then manipulated to depress the springs 14 and force the spurs 15 95 into the face of the adjacent shingle, the members 22 being next slid to engage the ends of said levers and thereby lock the same to the rule arms 17.

The straight edge A being thus securely 100 supported in position, the roofer in applying the next row of shingles, places same upon those portions of the previous row exposed above the straight-edge and nails them in place in the usual manner. Successive 105 rows may then be laid and secured by moving the gage to the "butt" portions of the row last secured and repeating the above described operation.

It will be noted by pivoting the levers 20 110 and arms 17 between the ears 12, that upon manipulation of the straight edge A said

levers may be actuated to release or depress the springs 14. Thus it is evident that no matter at what point along the straight edge the operator may be stationed, the gage can 5 be quickly and easily adjusted to the desired position upon the roof without the necessity for independent operation of the clamping members and a consequent shifting of position by the operator.

10 What is claimed, is:—

A shingling gage, comprising the combination with an elongated bar, of attaching members therefor, said members each in-

cluding a support, a clamp for the support, an arm pivoted to swing relatively to the support and having its free end secured to the bar, an actuating lever for the clamp mounted on the pivot of said arm, and means for releasably securing said lever to the arm.

In testimony whereof, I affix my signature, in the presence of two witnesses.

JACOB J. ENGBRECHT.
